CLAIM

The ornamental design for a medicament delivery device and cover assembly, as shown and described.

DESCRIPTION

FIG. 1 is a front view of the cover of the medicament delivery device and cover assembly;

FIG. 2 is a front perspective view of the medicament delivery device and cover assembly;

FIG. 3 is a rear view of the cover of the medicament delivery device and cover assembly;

FIG. 4 is a rear perspective view of the medicament delivery device and cover assembly;

FIG. 5 is a rear perspective view of the cover of the medicament delivery device and cover assembly;

FIG. 6 is a top left perspective view of the cover of the medicament delivery device and cover assembly; and,

FIG. 7 is a top rear perspective view of the cover of the medicament delivery device and cover assembly.

In the drawings, the dashed lines depict portions of the article that form no part of the claimed design. The dot-dash broken lines define the bounds of the claimed design and form no part thereof.

1 Claim, 7 Drawing Sheets

Related U.S. Application Data

division of application No. 16/504,725, filed on Jul. 8, 2019, now Pat. No. 11,426,520, which is a continuation of application No. 16/280,488, filed on Feb. 20, 2019, now Pat. No. 10,342,924, which is a continuation of application No. 14/803,821, filed on Jul. 20, 2015, now Pat. No. 10,238,806, which is a continuation of application No. 13/357,935, filed on Jan. 25, 2012, now Pat. No. 9,084,849.
